UNITED STATES PATENT OFFICE.

IRA M. THURLOW, OF BELOIT, WISCONSIN, ASSIGNOR TO P. B. YATES MACHINE COMPANY, OF BELOIT, WISCONSIN, A CORPORATION OF WISCONSIN.

RESAW-ROLL-SETTING MECHANISM.

1,209,780.

Specification of Letters Patent. Patented Dec. 26, 1916.

Application filed February 9, 1916. Serial No. 77,343.

To all whom it may concern:

Be it known that I, IRA M. THURLOW, a citizen of the United States, residing at Beloit, in the county of Rock and State of Wisconsin, have invented certain new and useful Improvements in Resaw-Roll-Setting Mechanism, of which the following is a specification.

The invention has for its primary object 10 a peculiarly simple and efficient mechanism for adjusting the feed rolls of a re-saw machine, the same providing for exceeding nicety of adjustment of the rolls within a wide range both independently and also in unison to secure self-centering.

In the accompanying drawings and in 15 the description based thereon is set forth a preferred embodiment of the invention, the same being susceptible, however, of embodiment in other and varied constructional forms without departing from the essence of the invention, or sacrificing its material advantages.

In the drawing, Figure 1 is a top plan 20 view of the feed roll mounting and set works; Fig. 2 is a side elevation of the same; Fig. 3 is an edge elevation of the set works showing the rack bars in cross section; and Fig. 4 is a detail view in top plan 25 showing a portion of the operating mechanism of the set works in a different position from that shown in Fig. 1.

Feed rolls 11, 11 arranged at one side of 30 the saw line are mounted upon the carriage 12 for movement toward and from said line, while the feed rolls 13, 13 are mounted upon the carriage 14 for similar movement on the opposite side of the saw line. The carriage 12 has secured thereto in fixed relation a rack bar 15 and the carriage 14 is similarly provided with a rack bar 16, these two rack bars being in superjacent planes and meshing respectively with pinions 17 and 18 coaxially mounted, the 35 former upon a tubular shaft 19 and the latter upon a solid shaft 20.

Fixed upon the shaft 19 of the pinion 17 40 is a hub-like member 21 provided with radially arranged equally spaced notches 22. The hub member is shown as having the 45 form of a notched disk but the form of said member is immaterial and it may be a member provided with radial arms having terminal sockets, the sockets being the functional equivalents of the notches. The shaft

20 of the pinion 18 is provided with a similar hub member 23 having radially opening notches 24.

The spaced relation of the sockets or notches of the two hub members is such 50 that the angular movement of the hub member equal to the distance between two of the notches is sufficient to move its feed roll carriage one-quarter its entire range of movement toward and from the saw line, 55 wherefore it follows that if a suitable member be engaged within one of the notches and the hub turned until said notch reaches the position formerly occupied by the next adjacent notch the feed roll will 60 have been advanced or retracted, as the case may be, a distance corresponding to one-quarter its total permissible travel. For the purpose of causing such angular movement of the hub members and shaft independently and also in unison suitable mechanism is employed, preferably that now to 65 be described.

Fixedly mounted and having the shaft 70 as a center is a sector 25 divided by a fin 26 into upper and lower portions provided with ratchet teeth 27 and 28. Pivoted at 29 adjacent to the notched periphery of the hub member 21 is a lever 30 having a handle 31 and a sector-engaging 75 latch 32 with a conveniently situated finger piece 33 connected with the plunger rod 34, the inner end of which is attached to a plunger catch 35 adapted to engage within one of the notches 22 of the hub 80 member 21. A second lever 36 is similarly pivoted at 37 adjacent the notched periphery of the hub member 23 and is provided with a handle 38, a sector-engaging latch 39, a conveniently arranged finger piece 40, a 85 plunger rod 41, and a plunger catch 42 for engagement within one of the notches 90 24 of the hub member 23.

The pivotal mounting 29 of the lever 30 95 is in a projection formed upon a plate 43 which is rigidly fixed to the hub member 21 and the pivotal mounting 37 of the lever 36 is likewise in the plate 44 which has a fixed relation to the hub member 23. The hub plates 43 and 44 extend beyond the 100 peripheries of their hub members 21 and 23 and are respectively provided with arcuate slots 45 and 46 concentric with the shaft 20 and in vertical register one with the other. Extending through the slots 45 105 110

and 46 is a clamping pin 47 provided with a wing nut by means of which the two hub plates 43 and 44 may be clamped together in fixed relation in any desired angular relation about the shaft 20 as a center.

It will be observed that the levers 30 and 36 do not have an inherent rigid relation to the hub plates 43 and 44, but are rigidly coupled therewith in a detachable manner by means of coupling rods. These two coupling rods are identical and the description of one will suffice for both. Having reference to Fig. 1, the coupling rod 48 is pivoted to the hub plate 44 at 49, the opposite end 15 of the coupling rod being provided with a hook 50 arranged to take over an eccentric or cam shaped latch 51 provided with an operating handle 52. The coupling rod 48 is encircled by a compression spring 53 bearing 20 at the outer end of the coupling rod upon the shouldered nut 54 and at its opposite end upon the stop 55 which is threaded upon said rod, and adapted to be seated within the hook formed by the nose 6 of the lever 36. 25 So arranged the lever is held in fixed relation to the hub plate and is substantially integral therewith to all intents and purposes. However, by releasing the hook 50 of the connecting rod from the latch 51 by swinging 30 the same by means of its handle 52 (see Fig. 4) the connection between the lever and its hub plate is rendered yielding under the influence of the compression spring 53 acted upon by the movable or slidable stop 55.

35 When the various parts of the set works are arranged with both the levers occupying an extreme position at say the left hand of the sectors and with their plunger catches in engagement with the notches 22 and 24, 40 the feed rolls will be equi-distant from the saw line and in their position of greatest separation. If, now, the lever 36 be grasped and moved to the position shown in Fig. 1 at the right of the sector, the hub member 23 45 will be angularly turned and the feed rolls 13 will be advanced toward the saw line one-fourth of their complete travel. If the plunger catch 42 be now released from the notches of the hub member 23 by means of 50 the finger piece 40 and the latch 39 be released from the teeth 28 of the sector and the lever be moved to the left until its plunger catch 42 engages within the next stop 24, the carriage 14 and the feed roll 13 may be advanced another quarter in the same manner. 55 Obviously the advance may be finally made less than a quarter by permitting the latch 39 to engage the sector at any point intermediate the two extreme positions of the lever. In the same manner the carriage 12 and the feed rolls 11 may be advanced and retracted by the actuation of the lever 30 and its engagement with the successive notches of its hub member 21.

60 65 The above description applies to gage saw-

ing, the levers being substantially rigidly connected with the hub members by means of the coupling or connecting rod as shown in Fig. 1. If, however, it is desired to have the feed rolls move toward and from each other in unison for self-centering, the two levers are brought into the desired relative adjustment or position, the hooks 50 of the coupling rods are released by means of the cam latch 52 and the two hub plates are 70 clamped together by means of the pin 47 and nut. The levers are now, in effect, "broken" and the connection between the lever and its hub member or plate is a rocking one about the points 29 or 37 and 55, and 75 the rolls can yield in opposite directions against the force of the compression springs 53, such yielding being made uniform by the clamping together of the two hub plates.

I claim:

1. In re-saw roll setting mechanism, the combination of a pair of feed rolls arranged on two sides of the saw line, a carriage for each roll movable along ways transversely of the saw line, co-axially arranged shafts, gearing connecting each of the shafts with one of the carriages, a hub member fixed on each shaft, a lever pivoted to each hub member, means to hold the free end of the lever in a selected position, and a yielding connection between the lever and hub at a point forming a triangle with the pivot and shaft. 85
2. In re-saw roll setting mechanism, the combination of a pair of feed rolls arranged on two sides of the saw line, a carriage for each roll movable along ways transversely of the saw line, co-axially arranged shafts, gearing connecting each of the shafts with one of the carriages, a hub member fixed on each shaft and provided with peripherally spaced notches, a lever pivoted to each hub member and including a releasable catch adapted to alternately engage one of the notches, means to hold the free end of the lever in a selected position, and a yielding connection between the lever and hub at a point forming a triangle with the pivot and shaft. 90
3. In re-saw roll setting mechanism, the combination of a pair of feed rolls arranged on two sides of the saw line, a carriage for each roll movable along ways transversely of the saw line, co-axially arranged shafts, gearing connecting each of the shafts with one of the carriages, a hub member fixed on each shaft, a lever pivoted to each hub member, means to hold the free end of the lever in a selected position, a yielding connection between the lever and hub at a point forming a triangle with the pivot and shaft, and means to transform the yielding connection to a rigid one. 100
4. In re-saw roll setting mechanism, the combination of a pair of feed rolls arranged on two sides of the saw line, a carriage for each roll movable along ways transversely 105

of the saw line, co-axially arranged shafts, gearing connecting each of the shafts with one of the carriages, a hub member fixed on each shaft, a lever pivoted to each hub member, means to hold the free end of the lever in a selected position, a yielding connection between the lever and hub at a point forming a triangle with the pivot and shaft, and means to couple the hub members together 10 in fixed relation.

5. In re-saw roll setting mechanism, the combination of a pair of feed rolls arranged on two sides of the saw line, a carriage for each roll movable along ways transversely 15 of the saw line, co-axially arranged shafts, gearing connecting each of the shafts with one of the carriages, a hub member fixed on each shaft, a lever pivoted to each hub member, means to hold the free end of the lever 20 in a selected position, a yielding connection between the lever and hub at a point forming a triangle with the pivot and shaft, means to transform the yielding connection to a rigid one, and means to couple the hub 25 members together in fixed relation.

6. In re-saw roll setting mechanism, the combination of a pair of feed rolls arranged on two sides of the saw line, a carriage for each roll movable along ways transversely 30 of the saw line, co-axially arranged shafts, gearing connecting each of the shafts with one of the carriages, a hub member fixed on each shaft and provided with peripherally 35 spaced notches, a lever pivoted to each hub member and including a releasable catch adapted to alternately engage one of the notches, means to hold the free end of the lever 40 in a selected position, a yielding connection between the lever and hub at a point forming a triangle with the pivot and shaft, and means to transform the yielding connection to a rigid one.

7. In re-saw roll setting mechanism, the combination of a pair of feed rolls arranged 45 on two sides of the saw line, a carriage for each roll movable along ways transversely of the saw line, co-axially arranged shafts, gearing connecting each of the shafts with one of the carriages, a hub member fixed on 50 each shaft and provided with peripherally spaced notches, a lever pivoted to each hub member and including a releasable catch adapted to alternately engage one of the notches, means to hold the free end of the lever 55 in a selected position, a yielding connection between the lever and hub at a point forming a triangle with the pivot and shaft, means to transform the yielding connection to a rigid one, and means to couple the hub 60 members together in fixed relation.

8. In re-saw roll setting mechanism, the combination of a pair of feed rolls arranged on two sides of the saw line, a carriage for each roll movable along ways transversely 65 of the saw line, co-axially arranged shafts,

gearing connecting each of the shafts with one of the carriages, a hub member fixed on each shaft, a lever pivoted to each hub member, means to hold the free end of the lever in a selected position, a coupling rod pivoted 70 to the hub member at one side of the pivotal connection of the lever, a releasable connection between the free end of the rod and lever, a stop fixed on the rod near its free end, a second stop slidable on the rod near 75 its pivoted end, a compression spring on the rod between the stops, and a rocking engagement between the sliding stop and the lever.

9. In re-saw roll setting mechanism, the combination of a pair of feed rolls arranged on two sides of the saw line, a carriage for each roll movable along ways transversely 80 of the saw line, co-axially arranged shafts, gearing connecting each of the shafts with one of the carriages, a hub member fixed on each shaft, a lever pivoted to each hub member, means to hold the free end of the lever 85 in a selected position, a coupling rod pivoted to the hub member at one side of the pivotal connection of the lever, a releasable connection between the free end of the rod and lever, a stop fixed on the rod near its free end, a second stop slidable on the rod near 90 its pivoted end, a compression spring on the rod between the stops, and a rocking engagement between the sliding stop and the lever, and means to clamp the hub members together 95 in fixed relation.

10. In re-saw roll setting mechanism, the combination of a pair of feed rolls arranged on two sides of the saw line, a carriage for each roll movable along ways transversely 100 of the saw line, co-axially arranged shafts, gearing connecting each of the shafts with one of the carriages, a hub member fixed on each shaft, a lever pivoted to each hub member, means to hold the free end of the lever 105 in a selected position, a coupling rod pivoted to the hub member at one side of the pivotal connection of the lever, a releasable connection between the free end of the rod and lever, a stop fixed on the rod near its free end, a second stop slidable on the rod near 110 its pivoted end, a compression spring on the rod between the stops, and a rocking engagement between the sliding stop and the lever, the two hub members having registering arcuate slots, and means to clamp the hub members together in fixed relation comprising a pin passing through the slot and a lock nut thereon.

11. In re-saw roll setting mechanism, the combination of a pair of feed rolls arranged on two sides of the saw line, a carriage for 115 each roll movable along ways transversely of the saw line, co-axially arranged shafts, gearing connecting each of the shafts with one of the carriages, a hub member fixed on each shaft, a lever pivoted to each hub mem- 120 125 130

ber, means to hold the free end of the lever in a selected position, and a yielding connection between the lever and hub at a point other than the pivotal point.

- 5 12. In re-saw roll setting mechanism, the combination of a pair of feed rolls arranged on two sides of the saw line, a carriage for each roll movable along ways transversely of the saw line, co-axially arranged shafts, 10 gearing connecting each of the shafts with one of the carriages, a hub member fixed on each shaft, a lever pivoted to each hub member, means to hold the free end of the lever in a selected position, and a yielding connection 15 between the lever and hub at a point other than the pivotal point, and means to transform the yielding connection to a rigid one.

13. In re-saw roll setting mechanism, the

combination of a pair of feed rolls arranged 20 on two sides of the saw line, a carriage for each roll movable along ways transversely of the saw line, co-axially arranged shafts, 25 gearing connecting each of the shafts with one of the carriages, a hub member fixed on each shaft, a lever pivoted to each hub member, means to hold the free end of the lever in a selected position, a yielding connection 30 between the lever and hub at a point other than the pivotal point, and means to clamp the hub members together in fixed relation.

In witness whereof I have hereunto signed my name in the presence of two subscribing witnesses.

IRA M. THURLOW.
